CLAIM

The ornamental design for a tilt truck, as shown and described.

DESCRIPTION

FIG. 1 is a front perspective view of a tilt truck showing my new design;

FIG. 2 is a rear perspective view thereof;

FIG. 3 is a front elevational view thereof;

FIG. 4 is a rear elevational view thereof;

FIG. 5 is a side elevational view, the opposite side elevational view being a mirror image;

FIG. 6 is a top plan view thereof;

FIG. 7 is a bottom plan view thereof;

FIG. 8 is a bottom perspective view thereof; and,

FIG. 9 is a front-perspective view, similar to FIG. 1 except illustrating the tilt truck of FIG. 1 with the lid removed.
